UNITED STATES PATENT OFFICE.

WILLIAM B. RUGGLES, OF BAYONNE, NEW JERSEY.

DRIER.

SPECIFICATION forming part of Letters Patent No. 636,852, dated November 14, 1899.

Application filed August 1, 1898. Serial No. 687,384. (No model.)

To all whom it may concern:

Be it known that I, WILLIAM B. RUGGLES, of Bayonne, county of Hudson, State of New Jersey, have invented a new and useful Drier, 5 of which the following is a specification.

My invention relates to improvements in driers of the type designed for the drying of sand and similar materials, its object being to provide an improved construction of the 10 same; and it consists in the features of construction hereinafter described and claimed.

In the accompanying drawings, forming part of this specification, Figure 1 is a vertical longitudinal section of the apparatus. Fig. 15 2 is an end elevation and partial section of the same at line 2 2 of Fig. 1, looking from left to right of said figure. Fig. 3 is a cross-section at line 3 3 of Fig. 1, looking from left to right; and Fig. 4 is an end elevation and 20 partial section at line 4 4 of Fig. 1; looking from right to left of said figure.

In the drawings, 5 represents a suitable base, on which the apparatus is mounted; A, a sheet-metal cylinder having circumferential 25 rings 6 and 7 riding, respectively, upon the carrying-rolls 8 and 9, which rolls are preferably grouped in pairs, as illustrated in Fig. 3, and are mounted in yokes 10, which swing on pivots 11. The rolls 9 have flanges 12 to 30 hold the cylinder from longitudinal displacement. The cylinder is also provided with a gear-ring 13, with which meshes a pinion 14, carried by a shaft 15, having a belt-drum 16 or other suitable means of receiving and conveying 35 power. The front or left-hand end of the cylinder A is open for nearly its entire diameter and extends into the drum 17, into the head of which drum enters a chute 18 for the delivery of the material, the chute extending 40 downwardly and inwardly, so as to deposit the same within the cylinder A, as shown in Fig. 1. The flap 19 covers a peep-hole which permits a view of the interior of the cylinder when in use. The pipe or stack 20 serves as 45 an outlet and may be connected with a blower or chimney or other means for producing any desired draft. The other end of the cylinder opens into a drum 21, at the bottom of which is a delivery-chute 22 for the material as it 50 passes from the machine.

Fixed within the cylinder A is a sheet-metal flue B, preferably "pear-shaped" in cross-

section or with its upper portion of inverted-V shape. This flue is supported in any suitable manner, as by means of hangers 23, the end of the flue extending, preferably, into the drum 21 and the relative operations of the cylinder and flue being such that the cylinder will serve as a return-flue for heated gases and lead them to stack 20. Connected with the other end of the flue is a pipe 24, preferably with a refractory lining 25, which pipe extends to a furnace or other source of heat. Arranged upon the inclined surface of the flue B are the series of angle-iron bars or deflectors 26, the lower ends of which are pivoted to the flue and the upper ends to an operating-bar 27. This bar extends from the drum 21 and is fitted with an operating-lever 28, by means of which the angular position 70 of the deflectors 26 may be adjusted for the purposes hereinafter described, the operating-bar working in notches in the bars 26^a.

Arranged upon the inner surface of the cylinder A is a series of buckets or angular steps 75 which serve as the cylinder is rotated to carry the material deposited in it upward and to drop it upon the top of the flue B, down the inclined surface of which it slides and is forwardly delivered by the deflectors, the degree 80 of forwarding the delivery of the material being determined by the angle at which the deflectors are set, the object of this arrangement being to adjust the apparatus according to the condition of the material. If very 85 wet, the deflectors are set at a high angle, so as to cause the material to be pushed slowly through the machine, and therefore thoroughly dried, whereas if the material is in less moist condition the deflectors can be set 90 at a greater angle and the material carried through more rapidly.

Access to the interior of the cylinder is given by the door 30 for the purpose of repair or cleaning.

The operation of the apparatus is readily understood from the drawings and foregoing description, the heated gases being delivered from a furnace through the pipe 24 into the apparatus, and the cylinder A being rotated 100 the sand or other material is delivered into the chute 18 upon the bottom of the cylinder A: Thus by the rotation of the cylinder this is carried by the buckets upward and dropped

down the chute to the flue B. The deflectors carry it step by step forward with each operation, and the parts being properly adjusted when the material has just been conveyed to 5 the other end of the apparatus, which has been thoroughly dried for the purposes desired, and is delivered from the cylinder through the chute 22, products of combustion, not only heating the materials as they pass 10 from the flue, but also as they return outside the flue and within the cylinder to the stack 20, come in contact with the material and serve to dry the same.

I claim—

- 15 1. In a drier, in combination, a stationary, open-end flue, a rotatable inclosing cylinder serving as a return-flue, means upon the cylinder for elevating and depositing the material upon the stationary flue, and adjustable 20 means upon the latter for conveying said material forward in said cylinder as it drops from said flue.
2. In a drier, the combination with a rotatable cylinder, having interiorly-arranged 25 buckets, of a stationary flue arranged therein having its top of inverted-V shape in cross-section and provided with a series of ribs or deflectors adjustable upon said V-shaped surface, as and for the purposes specified.
- 30 3. In combination, a revolute cylinder, an

axially-arranged imperforate fixed flue there-
in connected with a source of heat, said cyl-
inder and flue being interspaced sufficiently
to permit the flow of material under treat-
ment therethrough and to serve as a return- 35
flue for the heated gases, circumferentially-
arranged elevating means upon the interior
of the cylinder, and adjustable longitudinally-
conveying means upon the said flue, substan-
tially as and for the purposes specified. 40

4. In a drier, the combination of the hori-
zontal rotatable cylinder, one end communi-
cating with a discharge-chute, and the other
with an inlet-chute and a gas-outlet, an open-
end flue connected with a source of heat, and 45
so arranged in said cylinder that the latter
serves as a carrier for the material to be dried
and a return-flue for the heating-gases, the
buckets upon the interior of the cylinder for
elevating the material and dropping it upon 50
the flue, the forwardly-inclined deflectors
pivoted to the flue and the shifting rod for
adjusting the angle of the deflectors.

Signed at New York city, New York, this
29th day of July, 1898.

WILLIAM B. RUGGLES.
